The ornamental design for a core for electronic component, as shown and described.

DESCRIPTION

FIG. 1 is a perspective view of a core for electronic component showing our new design;

FIG. 2 is a front elevation view, with the rear elevation view being a mirror image of the front elevation view thereof;

FIG. 3 is a top plan view thereof;

FIG. 4 is a bottom plan view thereof;

FIG. 5 is a right-side view, with the left-side view being a mirror image of the right-side view thereof; and,

FIG. 6 is a cross-sectional view of the core for electronic component taken along the line VI-VI in FIG. 2.
